UNITED STATES PATENT OFFICE.

GUNTHER H. PETRI, OF BROOKLINE, MASSACHUSETTS.

APPARATUS FOR PRINTING ON WAXED PAPER AND THE LIKE.

1,387,941.

Specification of Letters Patent. Patented Aug. 16, 1921.

Application filed January 16, 1918. Serial No. 212,004.

To all whom it may concern:

Be it known that I, GUNTHER H. PETRI, a citizen of the United States, residing at Brookline, in the county of Suffolk and 5 State of Massachusetts, have invented new and useful Improvements in Apparatus for Printing on Waxed Paper and the like, of which the following is a specification.

This invention relates to printing on 10 waxed paper and the like. The invention is illustrated as it may be applied in connection with waxed paper used for wrapping loaves of bread, but it is applicable to waxed paper used for other purposes, and 15 to other varieties of coated or treated paper in which the treatment is such as to prevent successful direct printing on the treated paper.

In the preparation of printed waxed paper 20 and the like, as now manufactured, it is invariably necessary as far as I am aware, to print the paper before it is coated with the waterproof, germproof or other material which gives it its characteristic utility, and 25 after the paper has been so coated no further printing upon it can be done. There are several disadvantages in this, one being manifest at the present time when considerable stocks of prepared paper are in the 30 hands of bakers, ready printed with weights of the loaves that were to be packed therein, but which have been rendered unsuitable by reason of the order of the food administrator changing the standards as to the permissible 35 weights of loaves. It is one object of the invention to provide means by which these prepared wrapping papers can be utilized, by being reprinted with a corrected weight, according to the new standards with 40 which they will be used. In making articles such as envelops and bags of coated paper it is most economical to coat the paper while it is in strip form, before being made up into the envelops; but when it is desired that 45 printing on the paper shall register at a particular place on the envelop there is expense, difficulty and some waste, in making the printing previously done on the strip register on the envelop. It is therefore another 50 object, attained by the invention, to provide a process by which printing can be done upon made-up articles of wax paper. It is a further object to introduce economy, and expedition, and to reduce the investment of 55 capital required, in the manufacture of

waxed paper and the like, by providing so that the waxed paper can be waxed in quantity in blank form, and then can be printed with its various devices as wanted, little by little, without the necessity of doing the 60 printing before the waxing, and so breaking up the waxing operation into small individual operations.

The invention may be performed by various means, several of which are illustrated, 65 including that which at the present time is preferred as seeming to be simplest and most finished in its results as well as being effective and least expensive. The process, speaking generally, is to soften temporarily 70 the wax that coats the fibers and fills the interfibrous spaces of the paper, so that it is in a liquid state; and then while it is in liquid state to apply ink thereto by impression from type. The fluid wax and the more 75 or less fluid ink intermingle, and the ink thus gets access to the fibers of the paper, along the lines on which the impression is made, and soaks into them and produces its printing effect thereon; and such parts of it as 80 do not reach the fibers of the paper are imprisoned by the hardening of the wax which immediately follows, so that the effect of printing is attained, both by the ink getting 85 at the cellular structure of the paper and 90 by the ink intermingling with the wax below the surface, coloring it, and being held there permanently when the wax hardens. This effect is best done by softening the wax only 95 in the very places where the ink is to be deposited, and by doing it simultaneously with the depositions of the ink by passing the paper over a heated ink-bearing printing roll. The process may however be performed by applying heat preliminarily to a 100 zone of the paper as wide as the line of type that is to be printed thereon, softening the whole width of this zone, and then applying the ink before the wax has hardened. And although it has been found experimentally 105 that the process works well when heat is the softening agent; it appears that the process might be practised by the use of a solvent such as alcohol which may be applied along a path in which the printing is 110 immediately afterward to be done. In this case the ink mingles with the wax and the fibers, as before, and is held imprisoned upon evaporation of the solvent.

Apparatus used in practising the process 110

may take the simple form of a heated printing roll adapted to run on the paper just before the paper goes into the machine where it is to be cut and folded around the bread. This statement illustrates another field of its utility, for when so used it can, if desired, mark the date or hour on the wrapper, the print wheel being changed as necessary, thus being a field which could 5 not be entered satisfactorily by pre-printed paper without great waste. The apparatus may bear upon the supply roll of paper, applying to it the heat or solvent in advance of the roll applying the ink. Means for 10 applying the apparatus to a wrapping machine in which the waxed paper is used, and for adjustment of various parts to each other and to the wrapping machine, may be provided and are more fully described hereinafter. The invention may be embodied in 15 various forms of apparatus, and the process may be practised in variations from the precise form here described and illustrated. It is intended that the patent shall cover by 20 suitable expression in the appended claims, whatever features of patentable invention are here disclosed. In the accompanying drawings,

Figure 1 is an elevation of apparatus for 30 practising the invention viewed from the side of the course of paper that is being printed, unrolled and moving toward a wrapping machine.

Fig. 2 is an end elevation, looking in the 35 direction of travel of paper;

Fig. 3 is a plan;

Fig. 4 is a section of a detail, with the pipe and gas flame therefrom represented as having been rotated from its position at 40 Fig. 1 into the plane of section;

Fig. 5 is a side elevation of a modified form of apparatus;

Fig. 6 is a plan of the same;

Fig. 7 is a side elevation of a detail of 45 the printing type; and

Fig. 8 is a plan of the same.

Referring to the drawings 10 indicates a supply roll of waxed paper. This may, for example, be half a yard in diameter and 50 may consist of a strip of paper half a yard wide, or of such other size and width as conforms to the size of the loaves which are to be wrapped in the bread wrapping machine, whose location is indicated by one bar 11 55 of its frame but which is not otherwise illustrated.

The numeral 12 indicates a printing roll adapted to press upon the paper strip. As 60 illustrated in Fig. 1, the paper that is being printed is the outside layer of the supply roll, this thickness of paper being supported by the body of the roll; and the printing is done by the action of heat and ink conveyed simultaneously to the paper from the 65 roll 12. This roll gets its supply of heat

through the flame 13 of a Bunsen burner fed by a pipe 15 and controlled by a cock 16; and gets its supply of ink from an inking roll 17 having an ink-bearing body of felt 18. The axles of the rolls 17 and 12 are mounted 70 on pivoted arms, so that they can swing down around a fixed pivot 19 following down the diminishing diameter of the supply roll 10 as paper is drawn therefrom to be consumed. As illustrated in the drawing 75 there is a fork 20 holding the inking roll 17, and another fork 21 holding the printing roll 12. Both are loose on the pivot 19 which is a horizontal section of gas pipe from one of whose ends the arm 15 swings 80 with an ordinary gas pipe pivoted elbow. The other end of pipe 19 may be closed by a cap 23. Gas reaches the pivot 19 through a vertical supply pipe 22 which serves also as a support for the apparatus above described. The whole printing and heating apparatus thus described is attachable to the frame 11 of a wrapping machine by a bracket 24, wherein it may be adjusted and made fast at the desired horizontal distance 90 by a clamping screw 25; and it can be set and held at the desired vertical elevation by a bracket and screw 26 holding the upright pipe 22 which receives its supply of gas through a tube 27 whose flexibility 95 favors adjustment of elevation at will. The rolls 17 and 12 are so arranged as to be held down by gravity or other suitable force, roll 17 on the roll 12, and the latter on the paper that is to be printed. A fork 28 at the end 100 of the axle 29 of the printing roll 12 engages some suitable part of the gas pipe and arm 15 and causes that to swing up and down with the roll 12.

When the process is practised by means 105 of apparatus thus far described, the roll 12 presses down on the roll 10 and rolls on the surface thereon the strip of paper which is about to be drawn off. As fresh parts of the roll 12 come into contact with the paper 110 surface, they transmit thereto enough heat to melt wax thereon along the lines where the printing roll 12 comes in contact with the paper, which lines are the crests of the type formations thereon. The heat of the 115 roll 12 is thus used economically, except of course such as passes off by radiation, because that heat is used in melting wax only at the specific narrow lines where the new ink impression is to be; and only so much 120 heat need be used as is sufficient to make this molten for the brief period of time while the ink is flowing into and mingling with the temporarily molten wax. The adjacent portions of the surface of the paper 10 are undisturbed and remain of original texture and content.

A method which may be used either as an addition to that above described or as an alternative therefor is illustrated in Figs. 130

1 and 2 where a roller 30 is shown adapted to press against the main supply roll and to deposit upon it a suitable liquid such as alcohol, from bath or reservoir 31, and so 5 make a preliminary softened zone of wax upon which the printing roll 12 runs and does its work. The lapse of time between the application of liquid and the incidence of the type roll 10 gives opportunity for the 10 wax to be softened more deeply by the heat of the printing roller 12. However, if the printing roller be not heated the ink deposited by it may do its work owing to the flux produced by the solvent. If the 15 roller 12 be heated, its heat helps hasten the evaporation of the solvent after the ink has been deposited from its own surface, and also helps dry the ink quickly, thus leaving the printed paper equally dry and 20 ready for immediate use.

Figs. 5 and 6 illustrate another apparatus for performing the process in which a heating roller 32, mounted like the heating roller 12 as represented in Fig. 1, has a flat surface, 25 as seen in Fig. 6, and applies heat to a zone of the supply roll somewhat as the roller 30 applies a solvent to a zone thereof, within which zone the printing roll 33 tracks and does its work immediately afterward. The 30 impression of heat, solvent, or ink is not necessarily made directly against the supply roll as a bed. Figs. 5 and 6 show a plate 34 over which the paper passes from the supply roll 10 and on which it receives its printing. 35 In order to provide for continuous operation regardless of the diameter of the supply roll, the heating roll 32 and the printing roll 33 and the inking roll 35 are represented in Fig. 5 as being mounted on pivots which 40 permit them to follow down the diminishing size of the supply roll; and the printing bed plate 34 is pivoted, as at 36, and is pressed upward by the spring 37 which lifts it when the roll 33 is raised. When the 45 roll 33 presses down upon the bed 34 the latter is supported by the roll 38 at its free end, which rests on the surface of the supply roll and so swings down with the diminishing size of the supply roll.

50 When liquid is used as in Fig. 1 for distribution through roll 30 to the underside of roll 10, the roll 30 may automatically follow upward the diminishing size of the supply roll, by use of a device such as the 55 socket 39 and spring 40 therein illustrated, in Figs. 1 and 2, which maintain the bath 31 and roller 30 pressed upward against the supply roll of paper 10, whatever be the diameter thereof. The spring 40 is coiled 60 about the spindle 41 and fits rather closely within the socket 39. The upper end of the spindle projects into the bottom of the container for the liquid 31, and holds it stiffly upright; and the bottom end of the spindle 65 passes up or down as needed through the

bottom of the socket 39, being steadied by the hole therein and the spring surrounding it, or by such other means as may be advisable.

Figs. 7 and 8 show a style of type that 70 may be used, and illustrate how the transmission of heat from the roll 12 to the paper may be concentrated on the precise lines which carry ink, for these lines are raised above the body of the roll and so are 75 the only parts of the roll that touch the paper.

I claim as my invention:

1. A printing device for composite fabric having a printable core fabric and non-absorbent coating, comprising a holder for the fabric, adapted for the fabric to move forward; and means acting on the fabric to modify temporarily the coating along a restricted area; combined with means registering therewith for printing through the modified coating upon the core. 80

2. Apparatus for printing on non-absorbent fabric comprising a printing roll adapted to press thereon, an ink supply roll 90 adapted to press on the printing roll; means to mount said rolls on the frame of a mechanism in which a supply of the fabric is held; a gas burner arranged to heat said printing roll; and a pipe, conducting gas 95 to said burner and constituting a support for said printing roll.

3. Apparatus for printing on non-absorbent fabric comprising a printing roll adapted to press thereon; a swinging support 100 for the printing roll whereby said roll can follow the change of position of fabric that is being drawn from a supply roll; and a gas burner for heating said printing roll, mounted pivotally so that it can move with 105 the printing roll.

4. Apparatus for printing on non-absorbent fabric comprising a gas pipe and means to hold it rigid as a standard; a T-head therefor, constituting a pivotal support and 110 also a continuance of the gas passage; arms swinging therefrom; and a printing roller and co-operating gas burner supported by said arms.

5. A printing device for composite fabric 115 having a printable core fabric and a non-absorbent coating, comprising a holder for the fabric adapted for the fabric to move forward; and means comprised in one element for operating on the composite fabric 120 at a single contact with separate processes, one for modifying the coating and the other for printing on the core.

6. A printing device for composite fabric having a printable core fabric and a non-absorbent coating, comprising a holder for the fabric to move forward; a printing roll adapted to rest on the fabric; means to ink said roll and means to heat said roll preliminary to its contact with the fabric, 125 130

whereby upon contact the heat modifies the coating and the ink prints the core.

7. Apparatus for printing on non-absorbent fabric, comprising means to hold a roll of said fabric, combined with a gas pipe adjacent to the top of the roll; and a printing roller and a burner for heating the roller, both being pivoted on said gas pipe

and the roller being adapted to rest down by gravity on said roll of fabric, swinging ¹⁰ downward on said pivot as the roll of fabric diminishes.

Signed by me at Boston this 12th day of January 1918.

GUNTHER H. PETRI.
